BLASIUS BART, OF EAST ORANGE, NEW JERSEY.

METHOD OF FORMING ELECTROPLATED ARTICLES AND APPARATUS THEREFOR.

Application filed June 6, 1925. Serial No. 35,274.

The invention relates in general to the perfecting of a method and apparatus used in forming metallic deposits on molds and other structures by electrolytic deposition.

5 The invention specifically relates in its mechanical aspect to a cathode hanger for suspending articles to be coated in an electrolytic bath.

10 The primary object of the invention is to provide for economy in current consumption; to increase the efficiency of operation by causing the electric energy consumed to do its maximum amount of useful work in depositing the metal where desired, and at 15 the same time to minimize the destructive effect on the current conducting parts of the apparatus of the metal deposit forming where not needed or desired.

It has been appreciated heretofore that all 20 conducting surfaces connected with the object being coated and immersed in the electrolyte solution, will receive a deposit of metal and that the accumulating deposit necessitates increasing the current consumption 25 in order to complete the desired deposition action on the mold or other object under treatment. Attempts have been made to remedy this condition in several ways, such for instance, as by supporting the work to 30 be treated on small readily replaceable hooks which could be removed when they became coated. It has also been proposed to sleeve the main current conducting rod with rubber hose or similar insulation in 35 order to economize in current loss at least along the main arteries of current passage.

The present invention distinguishes from the prior art basically in that simplified means are provided for insulating all conducting 40 parts within the bath except where actual contact must be made with the mold or other surface to be coated and in minimizing the area of such exposed parts to the least possible area that will maintain the requisite 45 electric connection.

Another object of the invention is to provide a simple form of cathode plating hook which can be formed of separable sections so as to support any desired number of molds 50 or articles to be coated, and at the same time maintain the insulating properties featured in this disclosure.

In the form of the invention herein select-

ed for detailed discussion there is disclosed apparatus for forming an article inculding 55 a preformed element herein shown to be a brass ferrule and which is welded electrolytically to the metal shell forming the remaining portion of the article. In the present instance the replaceable ferrule constitutes part of the means for supplying the electric current to the prepared mold surface to be coated. Under such circumstances there is a tendency for the depositing metal to accumulate in a rough bead at the line of jointure between the ferrule and the formed surface, due to the concentration of electric energy at this point exposed to the electrolyte.

Another object of the invention therefore 70 is to provide an electrolytic weld between a preformed metal member and the shell or layer of metal being formed electrolytically and to insure such a form of welded jointure as will not be materially thicker than other 75 portions of the deposited metal layer and which will feature structural strength along the line of jointure.

Broadly this phase of the invention is attained by restraining the rate of flow of 80 the electrolyte to the line of jointure. In the instant case the insulation herein featured is continued about the ferrule almost up to the line of jointure of the same with the mold and the insulating elements are 85 designed and constructed to provide a constricted passageway for the electrolyte in its movement towards the line of jointure.

Another object of the invention is to provide an article of manufacture which will include a preformed metallic member, electrolytically welded to a shell formed electrolytically, and in which the line of jointure between the preformed and electrolytically formed parts will be neat in appearance and which will avoid the heavy bead and irregular accumulation of deposits usually formed at this point in such articles.

Various other objects and advantages of 100 the invention will be in part obvious from a consideration of the method features of the disclosure and from an inspection of the accompanying drawings, and in part will be more fully set forth in the following particular description of one method of practice.

ing the invention and in the inspection of a cathode hanger embodying certain mechanical features of my invention, and the invention also consists in certain new and 5 novel modifications of the preferred method and other features of construction and combination of parts hereinafter set forth and claimed.

In the drawings the figure is a view in 10 vertical axial section of a plating hook illustrating a preferred embodiment of the mechanical aspects of the invention, illustrating an instrumentality by means of which the method herein featured may be practiced and showing in completed form a resulting article of manufacture.

In the drawings the plating hook is shown to be formed of two separable and similar parts but it is understood that the hook 20 when in use may be formed of one or any number of parts assembled in alinement to provide a hook of the desired length and to accommodate the desired number of molds or other articles to be coated.

25 There is shown a conducting rod comprising an upper section 10 and a lower section 11, the upper section being provided with a hooked end 12 for making connection with the bus bars or other source of electric energy usual in electrolytic tank constructions. At the lower end of each rod is a metallic conducting coupling member 13 in screw threaded engagement therewith similarly threaded to the upper end of the 30 next adjacent lower rod section. It is appreciated that these coupling means may form a permanent part of either the upper or lower end of their associated rods and provide means for connecting the rods both 35 mechanically and electrically.

As each rod section is similar to each other section, the detailed description of any one will be sufficient for all.

40 The coupling 13 is provided at its lower end with an integral outstanding flange 14 the upper peripheral shoulder of which provides a support for a metal ferrule 15 which encircles the coupling and extends above the same for a short distance as noted particularly in the upper portion of the figure.

45 For a purpose hereinafter described the upper end of the ferrule is provided with an undercut peripheral groove 16 to constitute a mechanical lock for engaging with the electrolytic deposit as hereinafter described but it is understood that this groove is no material or necessary part of the present disclosure.

50 The upper end of the ferrule provides a support for a mold 17, in this case shown to be a glass mold including a curved underside 18 and having an outstanding flange 19. This particular form of mold is designed to form flange parabolic reflectors of 55 a well known type. It is understood that

the surface of the mold which is to receive the electrolytic deposit has been previously coated with a conducting material such as graphite or the silver layer shown at 20 in the lower part of the figure all as is well known in this art.

It will be understood from this construction that the ferrule 15 is in electric contact with the conducting rod at its lower and at its upper end in electric contact with the 75 silver coating on the underside of the mold.

It is a feature of this disclosure to restrain the usual rapid deposit of metal at the line of jointure 21 between the ferrule and the coating 20. For this purpose and 80 also to prevent electric leakage from the conducting rod and coupling an open top insulating collar 22 underlaps the flange 14 and extends upwardly about the ferrule 15 almost to its top, and in the instant case 85 approximately to the lower edge of the groove 16. In order to insure an available supply of electrolyte to the line of jointure and at the same time to minimize the exposing of the current conducting parts which 90 are carrying the maximum amount of electric energy, the upper end of the collar 22 is beveled downwardly and outwardly as shown at 23 and at an angle of approximately 45°. This construction provides an 95 exposing of the line of jointure to the electrolyte but minimizes the area of exposure. All other parts of the conducting members are insulated from the electrolyte.

Above the mold this insulation is provided by an insulating sleeve 24 preferably formed as a thin celluloid tube and shrunk on the conducting rod so as to have a friction tight fit. The insulating sleeve member may be used as one element of a clamp 100 for securing the mold in position and in this case a metal reinforcing ring 25 is threaded on the conducting rod and is enclosed by a boxing 26 continuous with the insulation forming the sleeve 24. In order 105 to provide the necessary cushioning engagement with the glass mold a rubber washer 27 is positioned between the clamp thus described and the upper inner face of the glass mold 18.

115 The lowermost insulating collar 22 differs from the collars used thereabove in the assembly in that its bottom wall 28 is closed thus forming an end knob 29 which will defeat any tendency to electric leakage through the opening in the bottom of the wall 28 necessary with the other collars in order to make connection with the rod section therebelow.

120 In operation and assuming that the several rod sections are disassembled, the upper rod sections with hook end is inverted with the hook down and the screw threaded end exposed. The upper glass mold with its 125 silver coating is positioned on the threaded 130

end and in engagement with the rubber washer. A ferrule is positioned in the collar of the next rod section and the sections screwed together thus forcing the ferrule into a light but positive bearing engagement with the silver coated mold.

The operation of assembling molds and rod sections is continued until finally the closing cap or knob 29 with its contained ferrule is screwed into engagement with the last rod section and the parts are then ready to be hung in the electrolytic tank and subjected to the depositing action of such tanks.

15 The deposit in this instance shown to be a copper deposit 30 is permitted to form as usual on the silver coating and to form in the undercut groove to provide a locking connection 31. Instead of the usual bead 20 which would otherwise form opposite this groove the layer of precipitated metal forms with a smooth outer surface as shown at 32 and rounds into the upper side of the ferrule without any appreciable increase in 25 thickness in material at this point than is present at the other portions of the depositing layer.

There is eventually formed a parabolic shaped reflector with an outlining flange at 30 its perimeter and a preformed ferrule which may preferably be of brass, at its apex.

By practicing the method herein featured it is possible to economize in current consumption and to efficiently direct the current 35 uniformly over the silver or other coating, and there is neither an excessive deposit at the point of electrical connection with the coating nor is there developed the electrical losses which heretofore has occurred at this 40 point. There is also avoided the loss both in current consumption and in materials due heretofore to the accumulation of metal deposit on parts which were not desired to be coated; and as electric contact is maintained 45 at all times with the coating it is not necessary to provide a separate means for insuring electric contact with the preformed metal surface.

While I have shown and described, and 50 have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:—

60 1. In the art of coating a surface of a mold with a layer of metal electrolytically deposited, the method which consists in placing an electric conductor in contact with the mold, exposing said mold and conductor to the electrolyte forming the bath,

and stopping off the deposit on the conductor except at the localized area of contact between the mold and conductor.

2. In the art of electrolytically welding a preformed metallic object to a metal shell 70 incidental to the formation of the shell on its mold, the method which consists in preparing the mold to receive a metallic deposit, placing the preformed object in contact with the prepared mold, exposing the 75 prepared mold and object to the action of an electrolytic bath, and stopping off the deposit from all portions of the object except along the line of contact between the object and the prepared surface of the mold. 80

3. In the art of forming an article having a ferrule, the method which consists in positioning the ferrule to abut the mold surface on which the article is to be formed, subjecting the mold surface and ferrule so 85 assembled to the action of an electrolytic bath, using the ferrule as a conductor of the electric current and stopping off the deposit from forming on the ferrule except adjacent its line of contact with the mold 90 surface.

4. In a device of the class described, the combination of a cathode hanger including a rod formed of a plurality of sections with the upper section provided with a hook, 95 coupling means at the lower end of each section, a ferrule supported on each coupling means and connected electrically with the conducting rod, a mold supported on each ferrule, means between adjacent coupling means for insulating the exposed portion of the conducting rod therebetween, and means for insulating the coupling means, said insulating means permitting exposure of the end of each ferrule supporting its associated mold and acting otherwise to defeat electric leakage from the conducting rod. 100

5. In a device of the class described, the combination of a cathode hanger including 110 a conducting member, a ferrule supported on the member and in electric engagement therewith, a mold supported on the ferrule, and insulating means enclosing all exposed parts of the member. 115

6. In a device of the class described, the combination of a cathode hanger including a conducting member, a mold supported from the member and having a surface in electric engagement therewith, and insulating means enclosing all exposed parts of the member thereby to minimize electric leakage from all parts of the member except where it supplies the mold surface. 120

7. In a device of the class described, the 125 combination of a cathode hanger, a flange secured thereto, a metal form ferrule supported on the flange and in electric contact therewith, and a mold supported on the ferrule. 130

8. In a device of the class described, the combination of a cathode hanger, a flange secured thereto, a metal ferrule supported on the flange and in electric contact therewith, a mold supported on the ferrule and insulating means enclosing the hanger above the mold. 70
9. In a device of the class described, the combination of a cathode hanger, a flange secured thereto, a metal ferrule supported on the flange and in electric contact therewith, insulating means enclosing the hanger above the mold, and about the flange and lower part of the ferrule. 75
10. In a device of the class described, the combination of a cathode hanger provided with a flange, a ferrule having an undercut groove adjacent its upper edge supported on said flange, an insulating collar surrounding said flange and extending upwardly therefrom about said ferrule substantially to the level of said groove, and a mold resting on said ferrule and supported thereby above the insulating collar. 80
11. A cathode hanger for use in an electrolytic tank, comprising a conducting member, means for supporting thereon an article to have a metal deposited electrolytically on the surface thereof, the portion of said member exposed to the electrolyte being of the least possible area necessary to provide the requisite electrical connection with the surface on which the deposit is formed. 85
12. A cathode hanger for an electrolytic bath, comprising conducting means, provided with a support for positioning thereon an object intended to receive a deposit of metal on a surface thereof, means for insulating all of said hanger which is to extend into the electrolyte except at the line of connection between said surface and said conducting means thereby to defeat tendency to form any metallic deposit on the conducting means. 90
13. A cathode hanger including a plurality of separate rods provided with means for securing the same, one in alignment with the other, each rod provided with means for mounting a mold thereon and in electric engagement therewith, each rod provided with an insulating member to enclose the exposed portions of the rod and each rod provided with insulating means for encircling the securing means. 95
14. A cathode hanger including a plurality of separate rods adapted to be disposed in vertical alignment, means for electrically and physically connecting adjacent ends of the rods, an end knob formed of insulating material for enclosing the lower end of the bottom rod to prevent electric leakage therefrom. 100
15. A cathode hanger including a rod provided at its upper end with means for making electric contact with a source of electric supply, a mold support adjacent its lower end, an insulating sleeve positioned on said rod and adapted to bear on the mold carried by the support. 105
16. A cathode hanger including a rod provided at its upper end with means for making electric contact with a source of electric supply, a mold support adjacent its lower end, an insulating sleeve positioned on said rod and adapted to bear on the mold carried by the support, and an open top insulating sleeve encircling the mold support. 110
17. A cathode hanger comprising a rod, a coupling flange threaded to the lower end of a rod, an insulating sleeve surrounding the coupling flange and providing a space between the sleeve and the rod for receiving a ferrule or the like. 115
18. A cathode hanger provided with means for supporting a mold in an electrolytic tank and provided with insulating means for defeating tendency of electric leakage therefrom, except to the parts of the mold desired to be coated. 120
19. In a device of the class described, the combination of a conducting rod having a flange adapted to support a ferrule on the rod, an insulating collar surrounding the flange and adapted to extend upwardly almost to the top of the supported ferrule, the upper edge of said collar being beveled downwardly and outwardly. 125
20. In a device of the class described, the combination of a conducting rod having a flange adapted to support a ferrule on the rod, an insulating collar surrounding the flange and adapted to extend upwardly almost to the top of the supported ferrule, the upper edge of said collar being beveled downwardly and outwardly at an angle of approximately 45°. 130
21. In a cathode hanger, the combination of a conducting rod provided with means for supporting a ferrule encircling the same and in electric engagement therewith, an insulating collar surrounding said means and means for insulating a part of the rod exteriorly of said collar. 135
22. In a device of the class described, the combination of a conducting rod, means for supporting a mold on said rod, and an insulating sleeve surrounding the rod and adapted to prevent electric leakage from the part of the rod above the mold. 140
23. In a device of the class described, the combination of a conducting rod, means for supporting a mold on said rod, an insulating sleeve surrounding the rod and adapted to prevent electric leakage from the part of the rod above the mold, and a rubber washer adapted to be positioned between the insulating sleeve and the mold. 145
24. In a cathode hanger, the combination of a conducting rod, a metal reinforcing ring 150

surrounding the rod, and a sleeve of insulating material surrounding the rod and ring.

25. An article of manufacture including a preformed metal ferrule having a groove adjacent one end and a layer of electrolytically deposited metal extended into said groove to lock the layer to the ferrule.

26. An article of manufacture including a preformed metal ferrule having a groove adjacent one end, a layer of electrolytically deposited metal extended into said groove to lock the layer to the ferrule with a smooth curve formed between the layer and ferrule along their line of juncture.

15 27. An article of manufacture including a metal ferrule, a layer of electrolytically deposited metal forming an electrolytic weld

with one end of the ferrule, and said deposited metal at the line of jointure with the ferrule being of substantially the same thickness as the other parts of the deposited layer. 20

28. A reflector including a parabolic shell having a metal ferrule at its apex, said shell including a backing of electrolytically deposited metal electrolytically welded to one end of the ferrule, and curving smoothly from the shell into the ferrule at the line of jointure. 25

Signed at Newark, in the county of Essex 30
and State of New Jersey, this 27th day of
May A. D. 1925.
